CLAIM

The ornamental design for a bath leg relaxation/support device, as shown and described.

DESCRIPTION

FIG. 1 is a top plan view of a bath leg relaxation/support device showing my new design;

FIG. 2 is a right side elevation view thereof, the left side elevation view being identical;

FIG. 3 is a bottom plan view thereof;

FIG. 4 is a front elevation view thereof;

FIG. 5 is a back elevation view (showing slight indentations where the back shin of the leg will rest) thereof; and,

FIG. 6 is an example of how the bath leg relaxation/support device design is used.
